Primary Examiner — Omeed Agilee*Assistant Examiner* — David Truong(74) *Attorney, Agent, or Firm* — The Sladkus Law Group(57) **CLAIM**

The ornamental design for a bottle with base, as shown and described.

DESCRIPTION

FIG. 1 is a perspective view of a bottle with base showing a new design;

FIG. 2 is a front view of the bottle with base of FIG. 1;
FIG. 3 is a rear view of the bottle with base of FIG. 1;
FIG. 4 is a left side view of the bottle with base of FIG. 1;
FIG. 5 is a right side view of the bottle with base of FIG. 1;
FIG. 6 is a top view of the bottle with base of FIG. 1; and,
FIG. 7 is a bottom view of the bottle with base of FIG. 1.
The broken lines depict portion of the bottle with base that
form no part of the claimed design.
